HOSPITAL TRAY

Lois E. Chandler, Dallas, Tex.

Application April 27, 1951, Serial No. 14,993

Term of patent 7 years

(Cl. D44—10)

To all whom it may concern:

Be it known that I, Lois E. Chandler, a citizen of the United States, residing in Dallas, in the county of Dallas, State of Texas, have invented a new, original, and ornamental Design for a Hospital Tray, of which the following is a specification, reference being had to the accompanying drawing, forming a part thereof.

I claim:

The ornamental design for a hospital tray, substantially as shown.

LOIS E. CHANDLER.
